UNITED STATES PATENT OFFICE.

AXEL WELIN, OF LONDON, ENGLAND, ASSIGNEE TO WELIN, DAVIT AND LANE & DE GROOT CO., CONSOLIDATED, A CORPORATION OF NEW YORK.

PULLEY-BLOCKS.

1,036,391.

Specification of Letters Patent. Patented Aug. 20, 1912.

Application filed January 30, 1912. Serial No. 674,321.

To all whom it may concern:

Be it known that I, AXEL WELIN, a subject of the King of Sweden, residing at Hopetown House, Lloyd's avenue, in the city of London, England, have invented new and useful Improvements in Pulley-Blocks, of which the following is a specification.

Multiple sheaved pulley blocks as at present constructed when being raised by the suspending rope with no load attached to them frequently tip up and topple right over, thus fouling the tackle, and making the raising of them a difficult and time wasting operation.

According to this invention this objection is overcome by employing eccentric instead of concentric sheaves as is usual in the suspended pulley block. The eccentric sheave 20 may be either above or below the other two but the rope or ropes must be so rove that the fastest moving part or parts passes over the uppermost sheave or sheaves.

Usually three sheaves are provided the middle sheave being eccentric to the two outer ones which are concentric to each other. The upper block is also sometimes provided with an eccentric sheave.

Preferably one end of the rope is attached to the bottom of the upper pulley block and is so roved that the outer or fastest moving part of the rope passes around the upper sheave of the lower block and preferably also the sheaves in both the upper and lower blocks turn on parallel axes, the eccentric sheave or sheaves preferably being made to overlap the others to economize space and render the operation more easy.

In order to illustrate the invention two examples will be given.

Figure 1 shows diagrammatically pulley blocks and a suspending rope constructed and arranged in accordance with one form of my invention, and Fig. 2 is a similar view of a modification.

In the first example shown diagrammatically at Fig. 1 the upper and lower blocks are similar each consisting of three sheaves of as above described the eccentric sheave of

the upper block being at the bottom and the eccentric sheave of the lower block being at the top. The rope is fixed to the upper block and is led around the outer sheave 4 of the lower block, the sheave 1 of the upper block, the sheaves 6 and 3 of the lower and upper blocks, and lastly over the middle sheaves 5 and 2 of the lower and upper blocks, its end being led to the place where power is applied. Preferably as shown the sheaves 2 and 5 are made to revolve about axes which are parallel with the axes of the sheaves 1 and 3 and 4 and 6 respectively, and as shown the sheave 2 is made to overlap the sheave 1 and 3 and the sheave 5 is made to overlap the sheaves 4 and 6. 65

In the second example shown diagrammatically at Fig. 2 the eccentric sheave of the lower block is at the bottom and the upper block is provided with four sheaves which may be concentric and both ends of the rope are hauled upon. In this case tracing from one end of the rope to the other, it passes over an end sheave 1 of the upper block, an end sheave 5 of the lower block, a middle sheave 2 of the upper block, 70 the middle sheave 6 of the lower block, the other middle sheave 3 of the upper block and lastly over the other outer sheaves 7 and 4 of the lower and upper blocks. 75

What I claim is:

1. The combination of an upper pulley block having a plurality of sheaves, a lower pulley block having a plurality of sheaves one of which is eccentric to the remainder, and a rope attached at one end to the upper pulley block and so roved in the sheaves of the upper and lower blocks that the outer part of the rope which moves fastest passes around the upper sheave of the lower block. 80

2. The combination of an upper pulley block having a plurality of sheaves and a lower pulley block having a plurality of sheaves all turning on parallel axes but one of which is eccentric to the remainder, and a rope so roved in the sheaves of the upper and lower blocks that the outer part of the rope which moves fastest passes around the upper sheave of the lower block. 95

3. The combination of an upper block having a plurality of sheaves and a lower block having a plurality of sheaves all turning about parallel axes but one of which is eccentric to the remainder and which overlaps the other sheaves of said block, and a rope so rove in the sheaves of the upper and lower blocks that the outer part of the rope which moves fastest passes around the upper sheave of the lower block.

AXEL WELIN.
